(57) **CLAIM**

The ornamental design for a light therapy device, as shown and described.

DESCRIPTION

This application is related to U.S. application Ser. No. 12/554, 872 filed Sep. 4, 2009, the entire contents of which are incorporated herein by reference.

FIG. 1 illustrates a perspective view of a light therapy device according to a specific example embodiment of the disclosure;

FIG. 2 illustrates a side elevational view of a light therapy device according to a specific example embodiment of the disclosure;

FIG. 3 illustrates a front elevational view of a light therapy device according to a specific example embodiment of the disclosure;

FIG. 4 illustrates a rear elevational view of a light therapy device according to a specific example embodiment of the disclosure;

FIG. 5 illustrates a top elevational view of a light therapy device according to a specific example embodiment of the disclosure; and,

FIG. 6 illustrates a bottom elevational view of a light therapy device according to a specific example embodiment of the disclosure.

The portions of the drawings rendered in broken lines are shown for purposes of illustration only and form no part of the claimed design.
